UNITED STATES PATENT OFFICE.

GEORGE H. MOORE, OF BROOKLINE, MASSACHUSETTS.

TEMPORARY BINDER.

Application filed April 25, 1921. Serial No. 464,224.

To all whom it may concern:

Be it known that I, GEORGE H. MOORE, a citizen of the United States, residing at Brookline, in the county of Norfolk and State of Massachusetts, have invented new and useful Improvements in Temporary Binders, of which the following is a specification.

This invention relates to a temporary binder which includes a base or holder and a plurality of wire arches, constituting movable leaf-engaging members mounted to oscillate on the base and adapted to enter orifices formed in loose leaves, and connect said leaves side by side in the form of a pack. A binder of the type to which the invention relates is disclosed by my Patent No. 905,559, dated December 1, 1908.

The present invention is embodied in certain improvements hereinafter described and claimed, on the construction shown by the above-mentioned patent, whereby the movable leaf-engaging members are adapted to be connected with the base member in such manner that each is capable of being independently manipulated, so that the members may be singly, successively and progressively engaged with and disengaged from the leaves, this capability being desirable for reasons which will hereinafter appear.

Of the accompanying drawings forming a part of this specification,—

Figure 1 is a plan view, showing the base member, the movable leaf-engaging members, and the movable member anchoring means of a temporary binder embodying the invention.

Figure 2 is an edge view of the same.

Figure 3 is a perspective view of one of the movable members.

Figure 4 is a section on line 4—4 of Figure 1.

Figure 5 is a fragmentary view similar to a portion of Figure 1, showing a modification.

Figure 6 is a plan view of the portion of the anchoring means shown by Figure 5.

Figure 7 is a fragmentary view similar to a portion of Figure 1, showing another modification.

Figure 8 is a section on the line 8—8 of Figure 5.

The same reference characters indicate the same parts in all of the figures.

In the drawings, 12 represents a flat base

member, which may be of any suitable form and construction, whereby it is adapted to support the anchoring means and the movable members hereinafter described. As 60 here shown, the base member is the back portion of a cover which connects two side pieces 13, adapted to be closed upon a pack of leaves. The base member may, however, be otherwise embodied.

I secure to the base member by suitable anchoring means as hereinafter described, a plurality of independent resilient movable members of bent wire, said members each including a leaf-engaging portion or arch 14, 70 and a short journal portion 15, from which the arch springs, the plane of the arch being substantially at a right angle with the journal.

The anchoring means above mentioned 75 may be of any suitable construction, adapted to be attached as by eyelets 16 to the base member, and having bearing bosses in which the journal portions 15 are adapted to turn independently to permit independent movement of each arch 14 to and from its leaf-confining position, and detents arranged to engage the free ends of the arches and releasably confine the latter in their leaf-confining positions, the formation of 85 the movable members and the anchoring members being such that stops are provided which maintain the arches in operative relation to the detents, each arch being independently maintained in said relation by 90 said stops.

In the embodiment of the invention shown by Figure 1, I have embodied the said anchoring means in a plurality of sheet metal plates 17, one for each movable member. Each plate is independently attached to the base member 12, and each is provided with a short bearing boss, forming with the base member a practically tubular bearing 18, in which the journal portion 15 of 100 one of the movable members is adapted to turn, and with a detent boss 23, having an orifice 19, a portion of the margin of which forms a detent adapted to engage the free end of the arch 14 of the same member. The 105 ends of the boss 18 form stops 18^a, one of which abuts against the arch 14, and the other against a shoulder or enlargement 20, formed on the journal portion, means being thus provided for preventing endwise 110 movement of the journal portion and bodily sidewise movement of the arch portion of

- the movable member. The free end of the arch portion of each movable member is adapted to be sprung or deflected sidewise from its normal position to enable a notch 5 21 in said free end to spring into engagement with the detent-forming edge of the orifice 19, but this does not amount to a bodily sidewise displacement of the arch. The said detent-forming edge is arranged 10 in the path in which the arch 14 moves, so that the notch 21, engages the detent boss when the arch, in swinging from the dotted line position shown by Figure 2, reaches the full line position.
- 15 The stops may be the edges 18^b of a slot formed between the ends of the boss 18', as shown by Figures 5 and 6, said stops abutting against opposite sides of one end portion of the arch 14'.
- 20 The anchoring means may include a detent boss 23', adapted to perform its function by cutting slits therein, as shown by Figures 5 and 6, these slots intersecting an orifice formed in the boss, so that spring 25 tongues 19^a are provided, adapted to snap into engagement with notches in the free end of the arch 14'.

The plate 17' of the embodiment illustrated in Figures 5 and 6 is provided along 30 opposite edges with the bosses 18', 23', the former receiving the journal 15' of the arch 14', and the latter having the spring tongues 19^a formed therein.

The independent plates 17 or 17' are 35 adapted to be variably spaced apart on the base member 12, in accordance with the length of the latter, each plate and its bosses, and the movable member associated therewith constituting an independent temporary binder unit, any desired number of 40 which may be applied to the base member. The anchoring means may include a single elongated plate 17^a, having a plurality of bearing bosses 18, and a single elongated detent boss having a plurality of orifices 19, as 45 shown by Figure 7.

A loose-leaf binder of this type in which arches of the movable members are independent of each other, is adapted to be more 50 conveniently operated than one in which the arches are connected and necessarily moved in unison, because the independence of the arches enables a portion of a leaf to be removed from a released or unlocked arch, while another portion remains in engagement with a locked arch.

This provision makes it possible to progressively engage with the binder, or to disengage from it one or several leaves, and 60 meanwhile to secure continuously in alinement that portion of the pack of leaves which is engaged, or is being progressively engaged with the arches.

In loose-leaf binders of this type in 65 which the arches are necessarily operated in

unison, it is more convenient and generally necessary to turn the entire binder to a position at right angles to its normal position when in use, in order to more easily engage the leaves with all the arches simultaneously, and when thus or otherwise manipulating the leaves in such binders it is difficult to avoid disarranging them, as no provision is made in such case for holding the leaves in alinement.

The improvement herein described operates much more simply and directly, and without any shifting of the cover from its normal position, inasmuch as only one arch at a time is unlocked (preferably the top 80 arch is unlocked first and the rest of the arches in consecutive order), and the paper lying flat on the cover member can be directly moved into position and progressively locked into the arches, without lifting the 85 paper from flat position on the cover member; or by reversal leaves may be thus progressively unlocked and swung out of position without displacing the rest of the pack.

I am enabled by providing a plurality of 90 movable members, each including a single arch and a journal which carries only one arch, to employ at least three arches, as shown by Figure 1, and to operate the arches singly, consecutively, and progressively in 95 such manner that the pack of paper shall be always held in control by at least two locked arches. When two arches are coupled together by a single journal portion, the arches must be unlocked simultaneously and 100 entirely release the paper from confinement, so that the sheets are liable to disarrangement. The single arch and journal may be employed in any combination of odd or even members, and may be arranged in groups 105 of three, which is desirable for the reason above stated. A single arch movable independently is much more easily released from locked position than an arch which is a member of a pair, connected by a journal 110 portion. The two arches thus connected, when engaged at their free ends with fixed detents, constitute springs, each opposing the displacement of the other from locked position, hence considerably more force is 115 required to unlock each arch of a pair than is required to unlock an independent arch. For this reason a temporary binder which includes a pair of arches, connected by a journal portion, is unsuitable for use by 120 young children in schools.

I claim:

1. A temporary binder comprising a base provided with a plurality of aligned tubular bearings, a plurality of leaf engaging members each including a resilient arch shaped section, the several axle sections extending laterally from one end of the arch shaped section, the several axle sections extending into the several bearings and each being 125

held in all positions thereof from longitudinal movement in its bearing; each arch shaped section having adjacent its other end a notch, and a plurality of detents on the 5 base each adapted to be engaged by the notch of one of the arch shaped sections when the latter is turned about the axis of its axle section into operative position, the parts being so related that the arched sections 10 may be singly, consecutively and progressively interlocked with and disengaged from a pack of leaves.

2. A temporary binder comprising a base, a plurality of plates separately secured to 15 said base and each provided with a tubular bead, a plurality of leaf engaging members, one for each plate, each including a resilient arch shaped section and a straight axle section extending laterally from one end of the 20 arch shaped section and into the tubular bead of the associated leaf engaging member, means for preventing relative movement in the direction of the length of the 25 axle section between the axle section and its bearing in all positions of the leaf engaging member, each arch shaped member having a notch formed therein adjacent its other end, and a detent on each plate for engaging said 30 notch when the leaf engaging member is turned to operative position about the axis of its axle section, the parts being so related that the arched sections may be singly, consecutively and progressively interlocked with and disengaged from a pack of leaves.

35 3. A temporary binder comprising a base, a plurality of plates separately secured to said base and each provided with two sub-

stantially parallel tubular beads, a leaf engaging member associated with each plate and comprising a resilient arch shaped section and a straight axle section extending laterally from one end of the arch shaped section and into one of the tubular beads on the plate, means for preventing relative movement between the axle section and bead 40 in the direction of the length of the axle section in all positions of the leaf engaging member, the resilient arch shaped section having a notch adjacent its other end, and a detent on the other bead of each plate 45 adapted to engage the notch of the arch shaped section when the leaf engaging member is turned to operative position about the axis of its axle section.

4. A temporary binder comprising a base, 50 a plurality of plates separately secured to said base and each provided with a tubular bead, a leaf engaging member associated with each plate and comprising a resilient arch shaped section and a straight axle section 55 extending laterally from one end of the arch shaped section and into the tubular bead on the plate, means for preventing relative movement between the axle section and bead in the direction of the length of 60 the axle section, and two detents on the plate adapted to engage the arch shaped section at diametrically opposite points when the leaf engaging member is turned to operative position about the axis of its axle 65 section.

In testimony whereof I have affixed my signature.

GEORGE H. MOORE.

Certificate of Correction.

It is hereby certified that in Letters Patent No. 1,441,873, granted January 9, 1923, upon the application of George H. Moore, of Brookline, Massachusetts, for an improvement in "Temporary Binders," an error appears in the printed specification requiring correction as follows: Page 2, line 127, claim 1, after the word "section" and before the comma insert the words *and a straight axle section extending laterally from one end of the arch-shaped section*; and that the said Letters Patent should be read with this correction therein that the same may conform to the record of the case in the Patent Office.

Signed and sealed this 6th day of February, A. D., 1923.

[**SEAL.**]

KARL FENNING,

Acting Commissioner of Patents.
